IRONER GEAR MECHANISM

John W. Racklyeft, Cleveland, Ohio, assignor to
The Apex Electrical Manufacturing Company,
Cleveland, Ohio, a corporation of Ohio

Application June 29, 1938, Serial No. 216,513

4 Claims. (CL. 38—59)

This invention relates to ironing machines and more particularly to a two-speed gear mechanism for use in connection with the driving of an ironer roll.

The conventional ironing machine provided for domestic use includes a rotating padded roll and a heated shoe adapted to press or iron garments advanced between the roll and shoe. Ordinarily the roll is rotated by means of an electric motor through suitable gearing at a constant speed and the speed maintained is intended to be one which will substantially remove the moisture from the average run of garments found in the household laundry. There are numerous occasions, however, where especially heavy garments are being ironed, in which the speed of the roll with respect to the shoe is such that some of the moisture remains in the garment and the garment is inefficiently or unsatisfactorily ironed.

To overcome this defect of the conventional ironer, it is among the objects of my invention to provide an ironing machine which is constructed and arranged to provide at least two different speeds for the ironing roll. One speed, or the normal speed, preferably corresponds to the speed of the roll in the conventional ironer and is about seven revolutions per minute. The other speed, which is a much lower speed, enables heavy garments or the like to be advanced between the roll and the shoe so that all of the moisture may be driven from the garment and the garment properly ironed. This second or lower speed is preferably about four revolutions per minute.

It is a further object of my invention to provide a simple, compact, two-speed gear arrangement for an ironer drive, wherein the desired speed may be easily selected by means of a lever conveniently accessible to the operator of the ironing machine.

It is a further object of my invention to provide a gear mechanism for an ironer in accordance with the preceding object, wherein a driven shaft is rotated at the same speed as a driving gear, to maintain a normal or conventional speed of the ironer roll and wherein the driven shaft is rotated at a lower speed than the driving gear, by means of a planetary arrangement between the driving gear and driven shaft.

It is a further object of my invention to provide a gear mechanism for an ironer in accordance with the preceding objects, wherein a sun gear is controlled to maintain either a direct drive or a lesser rotational speed between the driving gear and the driven shaft.

It is a further object of my invention to pro-

vide a gear mechanism in accordance with the preceding object in which the sun gear is axially shifted to effect speed changes in the driven shaft.

5 Additional objects, relating to simplicity in construction and economies in manufacture, will become apparent from the following description and the appended drawing, wherein:

Figure 1 is an end view with parts in section 10 of an ironer mechanism embodying my invention;

Figure 2 is an elevation with parts broken away taken along the lines 2—2 of Figure 1;

15 Figure 3 is a sectional view taken along the plane indicated at 3—3 of Figure 2;

Figure 4 is a sectional view similar to Figure 3, showing the sun gear shifted to obtain a low speed drive.

I have shown an ironer gear mechanism made 20 according to my invention in an ironer indicated generally at 8, which comprises a supporting stand 1, a bed frame or top 8, a gear case 9 and a roll and shoe 10 and 11, respectively, arranged in the usual manner. Preferably the shoe is fixed

25 with respect to the bed frame 8 upon which it is supported and the roll is of the type adapted to move toward the shoe. A power unit in the form of an electric motor 14 is supported beneath the bed frame 8 and suitable drive mechanism is interposed between the power unit and the roll to effect a lateral shifting of the roll toward the shoe. The specific mechanism employed to shift the roll toward the shoe forms no essential part of my invention, but is preferably of the type

30 shown in the patent to Racklyeft No. 2,087,447, July 20, 1937. The gear case 9 may be of a rigid cast construction provided with suitable bosses or bearings to rotatably support the ironer roll driving shaft 18, which shaft is rotated with respect to the shoe by means of a worm gear drive 17—18, the pulley 19 and the belt 20 leading therefrom to the pulley 21 on the motor. Preferably that portion of the case enclosing the worm drive and the mechanism for shifting the 35 roll is enclosed within the compartment 12 which may be partially filled with lubricant to insure the quiet, smooth operation of the parts therein.

40 To transmit the drive from the pulley 19 to the worm gear shaft 18, which will hereinafter be referred to as the driven shaft, the said shaft 18 is projected through the wall of the compartment 12 and supports upon its projecting end the speed change mechanism of my invention indicated in its entirety as at 25. The worm gear

45 50 55 55

shaft 18 is preferably threaded as at 26 on its outer end to receive an internally threaded hub of a gear carrier 27. The pitch of the threads in the connection between portions 26 and 27 is selected with respect to the rotation of the shaft to effect a tightening of the threaded connection. The gear carrier member 27 is provided with a circular periphery having a smooth rotating fit as at 28 in the pulley member 19. A retaining collar such as 29 is fitted within the pulley 19 to mount the pulley for free rotation with respect to the gear carrier 27. Integrally formed or securely fixed to the pulley 19 is an internal gear member 31 having teeth adapted to mesh with the teeth on a planet gear 32, rotatably supported by means of pin 33 on the gear carrier 27. The hub portion of the gear carrier is preferably extended laterally beyond the threaded part thereof to provide a sleeve upon which is rotatably mounted a sun gear 35 having teeth 36 adapted to mesh with the teeth of the planet gear 32. In addition to being rotatably supported upon the sleeve of the gear carrier hub the sun gear is adapted to have a limited axial movement which in one position, as shown in Figure 3, brings lug 37 thereon into locking engagement with pin 38 carried within a groove 39 formed in the gear carrier.

With the sun gear in the position shown in Figure 3, it will be observed that rotation of the sun gear with respect to the gear carrier is prevented by the interlocking or abutting arrangement of the lug and pin 37-38, and that with such rotation prohibited, the planet gear 32 is restrained from rotation upon its own axis. Restraint of the planet gear results in rotation of the gear carrier and sun gear bodily in response to rotation of the pulley 19 and the internal ring gear 31. The gear carrier being fixed to the driven shaft 18, the driven shaft 18 turns at the same rotational speed as the pulley 19 so as to establish and maintain a direct drive between the pulley 19 and the shaft 18.

To bring about a reduced or low speed drive through the gear mechanism of my invention, the sun gear 35 may be shifted axially to the position shown in Figure 4, wherein the lug 37 and the pin 38 are separated from each other. In this position of the sun gear, a lug 41 at the outer end thereof is brought into engagement with a boss or projection 42 carried by a detachable section 43 of the gear case. The engagement of the sun gear with the gear case through parts 41-42 prevents rotation of the sun gear and thus provides a reaction for the planet gear 32.

By referring to Figure 2, it will be observed that with the ring gear 31 being rotated in the direction of the arrow 45 and the sun gear 35 being restrained from rotation, the planet gear 32 will be caused to rotate upon its own axis and at the same time to progress around the periphery of the fixed sun gear 35. The progression or planetary movement of the planet gear will cause the gear carrier 27 to rotate in the direction of the arrow 45 but at a lower rotational speed than the speed of the driving ring gear 31. The difference in rotational speed between the driving gear 31 and the gear carrier or driven shaft 18 will be determined by the ratio of the sun, planet and ring gears employed.

It will be understood from the above description of the gear mechanism in connection with the position of the parts in Figure 4, that the ironer roll driving shaft 16 will be rotated at a low speed (about half direct drive speed) so as

to efficiently iron heavy garments or garments containing considerable moisture. It will also be understood that the gear reduction will bring about a more powerful rotative force in the ironer roll to iron such heavy garments without undue strain upon the electric motor.

To maintain the ironer gear mechanism in either of its selected speeds, I prefer to employ a resilient latch device which includes a pair of annular grooves 48 and 49 formed on the inner periphery of the sun gear and a ball 50 normally pressed into one or the other of said grooves by a spring 51. I have found that the spring-pressed ball insures that the sun gear will not be casually or inadvertently moved from its selected position by the force of drive or movement of the parts. The sun gear may be manually shifted from either of its selected positions by means of a shifting yoke 52 and lever 53. The yoke 52 is provided with a pair of arms adapted to embrace the end of the sun gear and carries at the ends of the arms, pins 54 adapted to ride in the peripheral groove 55. The yoke 52 is keyed or otherwise rigidly secured to a shaft 56 rotatably mounted in the gear case part 43 and the oscillation of the shaft is controlled by moving the lever 53 as indicated by the dotted-line position of Figure 4.

In connection with the resilient latching means provided for the sun gear and the device shown for manually shifting the sun gear, it is pointed out that other latching and shifting devices may be substituted for those I have shown, depending upon the particular application or installation of the gear mechanism.

In operation the electric motor 14 is started in the usual manner by operating switch, not shown, and the rotation of the motor is imparted by way of belt 20 to the pulley 19. Ordinarily the gear 17 is continuously rotated and by means of clutches, not shown, this rotation is imparted to the roll shaft 16. Other mechanism, not shown, is automatically actuated to shift the roll 10 toward the shoe 11. Generally the gear mechanism of my invention is operated with the sun gear in the position shown in Figure 3 so that a direct drive is maintained between the pulley 19 and the driven shaft 18. When it is desired to rotate the ironer roll 10 at a lower speed, the operator moves the lever 53 to the position shown in Figure 4, whereby the planet gear is caused to progress about the sun gear and rotate the driven shaft 18 at a lower rotational speed than the speed of the pulley 19.

Although I have shown and described one form of my invention in considerable detail, it will be appreciated that numerous changes may be made therein without departing from the scope of the invention as defined in the following claims.

I claim:

1. An ironer comprising a gear case, an ironer roll shaft rotatably mounted in said gear case, a motor mounted beneath the gear case, a driven shaft arranged transversely of the ironer roll shaft between said roll shaft and motor, belt pulleys on said motor and driven shaft connected by a belt, a planetary gear speed change mechanism interposed between the driven shaft pulley and the driven shaft, said mechanism comprising a gear carrier fixed to and supported by the driven shaft, a planet gear mounted on said carrier, a ring gear fixed to the driven shaft pulley, an axially movable sun gear in constant meshed engagement with the planet gear, means connected to said sun gear projecting exteriorly of

the gear case to provide a manual control of said speed change mechanism through axial movement of said sun gear and means on said gear case adapted to engage said sun gear to afford a reaction lock for said planet gear.

2. An ironer comprising a rotatable roll, a shoe, and means to rotate the roll with respect to the shoe, said means including a gear case having a detachable gear case section, an ironer roll shaft in said gear case, a driven shaft adapted to rotate said roll shaft having one end thereof housed within said detachable gear case section, a change speed mechanism carried by the end of the driven shaft housed within the detachable gear case section, said mechanism including a gear carrier fixed to the end of the last-named shaft provided with a peripheral bearing portion, a belt pulley mounted on said bearing portion provided with a ring gear, a planetary gear mounted on said gear carrier in mesh with said ring gear, an axially slideable sun gear in mesh with said planetary gear, manually operable means having a portion projecting upon the exterior of said detachable gear case section and a portion operatively engaging said sun gear, whereby the sun gear may be shifted axially into engagement with the wall of the detachable gear case section or away from said wall to control the drive through said change speed mechanism.

3. An ironer comprising a rotatable roll and a heated shoe, mechanism to effect relative movement between said roll and shoe, means to drive said roll at low and high speeds comprising a driven shaft operatively connected to the roll, a driving gear mounted for rotation on said shaft, a gear carrier fixed to rotate with said shaft, a planet gear on said carrier in mesh with said driving gear, a gear case enclosing said means and a reaction member carried by said gear case, a sun gear in mesh with said planet gear adapted to be

clutched into operative engagement with said shaft or into engagement with said reaction member, said sun gear when in engagement with said member being restrained from rotational movement to effect a planetary movement of said planet and gear carrier to establish a low-speed drive, said sun gear when clutched into operative engagement with said shaft providing a reaction for said planet to establish a high-speed drive and a manually-operated control connected to said sun gear projecting to the exterior of the gear case.

4. An ironer comprising a rotatable roll and a heated shoe, mechanism to effect relative movement between said roll and shoe, means to drive said roll at low and high speeds comprising a driven shaft operatively connected to the roll, a driving gear mounted for rotation on said shaft, a gear carrier fixed to rotate with said shaft, a planet gear on said carrier in mesh with said driving gear, a gear case enclosing said means and a reaction member carried by said gear case, a sun gear in mesh with said planet gear adapted to be clutched into operative engagement with said shaft or into engagement with said reaction member, said sun gear when in engagement with said member being restrained from rotational movement to effect a planetary movement of said planet and gear carrier to establish a low-speed drive, said sun gear when clutched into operative engagement with said shaft providing a reaction for said planet to establish a high-speed drive and a manually operated control having a portion projecting exteriorly of the gear case and a second portion within the gear case, said second portion selectively movable in one direction to establish a connection between said sun gear and said reaction member and movable in another direction to free the sun gear of the reaction member.

JOHN W. RACKLEYFT.
